DOOR LATCH

Filed July 14, 1928

Inventor
George Sfiris

By *Watson E. Coleman*
Attorney

UNITED STATES PATENT OFFICE

GEORGE SFIRIS, OF CORPUS CHRISTI, TEXAS

DOOR LATCH

Application filed July 14, 1928. Serial No. 292,745.

This invention relates to door latches and more particularly to a latch of that type wherein a swinging bar is engaged in an eye to secure a closure.

5 An important object of the invention is to produce in a device of this character a structure such that the bar may be firmly locked in the eye to prevent displacement thereof by an article inserted through a crack in the door or any similar means.

A further and more specific object of the invention is to provide in a construction of this character an eye formed with a branching slot, in one branch of which the end of 15 the bar may be engaged in the ordinary manner, the bar being movable after its engagement into a second branch of the slot from which it may not be disengaged except by movement to the first named branch.

20 A still further object of the invention is to provide in a structure of this character means for locking the bar in the second branch of the slot.

These and other objects I attain by the 25 construction shown in the accompanying drawing, wherein for the purpose of illustration is shown a preferred embodiment of my invention and wherein:—

Figure 1 is a plan view of a door latch constructed in accordance with my invention, parts being shown in solid lines in the locked position and in dotted lines in the position in 30 which the latch bar may be disengaged;

Figure 2 is a section on the line 2—2 of 35 Figure 1;

Figure 3 is a section on the line 3—3 of Figure 1;

Figure 4 is a section on the line 4—4 of Figure 1.

40 Referring now more particularly to the drawings, the numeral 10 indicates a hook bar pivoted at P to one or two relatively movable members M and M' which may constitute a door and door frame. The hook bar 45 10 corresponds in all particulars to the ordinary

hook bar with the exception of the fact that the bill 11 of the hook is provided with a longitudinal prolongation 12 of the hook bar, all portions of which are downwardly offset with relation to the hook bar.

50 The terminal portion of this prolongation is preferably turned upwardly, as indicated at 13.

In combination with a hook of this character, I secure to the other of the members M, 55 M' an eye having a substantially L-shaped opening, one branch 15 of this opening substantially aligning with the latch hook 10 in one position of this hook and the other branch 16 extending at right angles to the branch 15 60 and being arranged in the arc of swing of the bill 11 of the hook. The wall 16^a of the branch 16 which is remote from the pivot P of the hook bar is spaced from this pivot a distance greater than the distance from the pivot to the bill 11 and a distance less than the distance from the pivot of the hook to the terminal 13 of the prolongation. It will be 65 obvious that the hook may be engaged in the eye at the branch 15 of the slot but that if it is subsequently moved to the branch 16 thereof, it may not be removed by a vertical swinging movement, for the reason that the terminal portion 13 will underlie the far edge 70 wall 16^a of the branch 16 and prevent such vertical swinging movement. It must, therefore, be returned to the branch 15 before it 75 may be disengaged.

Upon the shorter wall 17 of the branch 15 80 of the slot, I provide a bearing 18 which is directed transversely of the branch slot 16 and aligns with the inner end thereof. In this bearing is slidably and rotatably mounted a bolt 19, one end of which is provided with an operating head 20.

85 The opposite end of this bolt has a hook 21. This bolt may be shifted over the branch 16 of the slot and rotated to oppose the hook 21 to the outer or longer wall of this slot. By 90 then withdrawing the bolt, the hook engages

over this wall and the bolt forms a stop, preventing movement of the bar which will permit alignment of its hook 11 with the branch 15 of the slot. This bolt forms a keeper which is practically unwithdrawable by manipulation of any element which may be inserted through a crack in the door.

Since the construction hereinbefore set forth is capable of a certain range of change and modification without materially departing from the spirit of the invention, I do not limit myself to such specific structure except as hereinafter claimed.

I claim:—

1. In combination, a pivoted hook bar and eye for engagement with the hook bar having a slot provided with two branches, said hook bar when engaged with one branch of the slot of the eye being disengageable therefrom by oscillation in its general plane of swing and when engaged in the second branch thereof having coaction with the eye preventing such disengagement, the hook bar being transversely oscillatable to shift the same from one to the other of said branches of the slot, and means upon the eye positionable to prevent shifting of the hook bar from one to the other of the branches of the slot.

2. Means for securing relatively movable members against movement with relation to one another including a hook bar pivoted to one of the relatively movable members and having a substantially U-shaped forward end providing a prolongation of the bar which is offset in the general plane of the bar, an eye secured to the other of the members and having a substantially L-shaped slot one branch of which is substantially radially aligned with the pivot of the hook, the other branch of the slot having the wall thereof which is remote from the pivot of the hook spaced from such pivot a distance less than the combined length of the hook bar and its extension and the opposite wall thereof spaced from the pivot a distance less than the length of the hook bar from the pivot to the bill.

3. Means for securing relatively movable members against movement with relation to one another including a hook bar pivoted to one of the relatively movable members and having an extension upon the terminal of the bill thereof providing a prolongation of the bar which is offset in the general plane of the bar, an eye secured to the other of the members and having a substantially L-shaped slot one branch of which is substantially radially aligned with the pivot of the hook, the other branch of the slot having the wall thereof which is remote from the pivot of the hook spaced from such pivot a distance less than the combined length of the hook bar and its extension and the opposite wall thereof spaced from the pivot a distance less than the length of the hook bar from the pivot to the bill, and a longitudinally shift-

able bolt for cutting off communication between the branches of the slot.

thereof spaced from the pivot a distance less than the length of the hook bar from the pivot to the bill, and a bolt shiftable transversely of the inner end of the last named branch of the slot to prevent disengagement of the hook bar therefrom, said bolt having at its end a hook engageable with the outer wall of the last named wall of the last named slot, said bolt being mounted for rotation whereby to shift said hook out of or into alignment with said wall.

10 In testimony whereof I hereunto affix my signature.

GEORGE SFIRIS.
